ATTORNEY

UNITED STATES PATENT OFFICE.

HENRY C. KEELER, OF RETSIL, WASHINGTON.

BOOK STRAP.

Application filed January 16, 1926. Serial No. 81,671.

My invention relates to improvements in luggage carrying straps of the form disclosed in my prior Patent No. 1,580,256 issued April 13, 1926, and is an improvement 5 upon the book carrier shown and described in United States Letters Patent No. 1,580-256 issued to me April 13, 1926, and the object of my invention is to provide a book strap that is simple and inexpensive in construction, easy and convenient to adjust onto books or other luggage and that is readily releasable manually, but will not become loose on the books or luggage that is being carried therein.

10 Other and more specific objects will be apparent from the following description taken in connection with the accompanying drawings, wherein—

Figure 1 is a perspective view of my book strap showing the same applied to books;

20 Fig. 2 is a perspective view of the strap with the books removed; and

Fig. 3 is a view in side elevation of the strap.

25 Referring to the drawings throughout which like reference numerals indicate like parts, 5 is a flexible strap having a clip 6, preferably in the form of a metal disc, secured to one end thereof, said disc having an opening 7 through which the end of the strap may be passed in securing the strap to the disc. The strap 5 is shaped to form a loop and the other end of the strap is passed through the hole 7 in the clip 6 from the 30 outside toward the inside of said loop and said last named end is made fast as at 8 to a buckle or clamp member 9 that is slidable on that portion of the strap substantially opposite to the clip 6. The buckle 9 may be of any suitable standard construction that is capable of being quickly clamped onto the strap at any point and also capable of being quickly released from said strap.

35 It will be obvious that the end portion of the strap 5 that is connected with the buckle 9 extends across the loop, as at 10, and divides said loop into a lower book receiving part 12 and an upper handle portion 11 arranged to be grasped by the hand or slipped 40 over the arm. It will further be noticed

that the strap 5, when connected as shown and described, has no loose ends but is in effect an endless book strap of very simple, convenient and inexpensive construction.

In applying the strap to books 14, said books are placed within the lower book receiving part 12 so that that portion of the strap adjacent to the end which is made fast to the clip 6 passes under said books and the portion 10 of the strap 5 extends across the 55 top of the books. The buckle 9 is adjusted on the strap into a position in which it is just below the top edges of the books and the clip 6 is adjusted so it is just below the top edges of the books when the strap is 60 drawn tight. In this position the strap, after passing through the clip 6, passes upward and thence across the tops of the books 14 and thence downward to the buckle 9 and the books are securely and tightly held in 65 such a manner that they will not readily drop out of the strap accidentally but may be very quickly and easily released therefrom.

The foregoing description and accompanying drawings clearly disclose a preferred embodiment of my invention, but it will be understood that this disclosure is merely illustrative and that such changes in the invention may be made as are within 70 the scope and spirit of the following claim.

What I claim is:

A book strap comprising a clip having a hole therein, a single strap, one end of which is secured to said clip by means of said hole, 75 the other end of said strap being passed through said hole in said clip thereby forming a loop and then extending across said loop and dividing the same into an upper handle portion and a lower book receiving 80 portion, and a buckle member secured to the last named end of said strap and slidable on said strap on the side of said loop substantially opposite to said clip and arranged to be clamped on said loop in adjusted 85 positions.

In witness whereof, I hereunto subscribe my name this 9th day of January, A. D. 1926.

HENRY C. KEELER.
